UNITED STATES PATENT OFFICE.

GIDEON ANDERSON, OF NEW YORK, N. Y., ASSIGNOR TO WILLIAM WEST, OF NEW YORK, N. Y.

TILTING TABLE.

1,299,894.

Specification of Letters Patent.

Patented Apr. 8, 1919.

Application filed December 13, 1917. Serial No. 206,898.

To all whom it may concern:

Be it known that I, GIDEON ANDERSON, a subject of the King of Sweden, and resident of the city of New York, in the county of Bronx and State of New York, have invented certain new and useful Improvements in Tilting Tables, of which the following is a specification.

My invention relates to an improved tilting table that may be used for various purposes, medical or otherwise, but which is intended primarily for use in the home as a support upon which a person may rest at certain angles of inclination for the purpose of exercising within limits the vascular system, for curative or health purposes; this being accomplished by having the table upon which the user rests tilted at a series of prescribed angles below the horizontal.

In order that the table may be tilted to a desired angle and adjustably maintained in that position, novel means to such end are provided; and in order that the table when not in use as a health promoting device may have the appearance of an ordinary couch, I have constructed the same in a manner to permit of all the table tilting and supporting mechanism being conveniently shifted to a position out of sight when not in use.

Other features and advantages of the table will be referred to in the detailed description of the invention which follows:

Referring now to the accompanying drawings forming part of the specification—

Figure 1 is a side elevation, partly in section, of a tilting table embodying my invention, with the table shown in raised or open position in full lines and in lowered or closed position in dotted lines.

Fig. 2 is a bottom view of the table with the parts in closed position, that is, swung upward beneath the table proper.

Fig. 3 is an enlarged fragmental view showing in side elevation a part of the table tilting mechanism.

Fig. 4 is an end view, looking from the left in Fig. 3, with the frame and rocker in section and with the operating lever of the tilting mechanism in position.

Fig. 5 is a horizontal section taken on the line 5—5 of Fig. 3.

Fig. 6 is an enlarged vertical section taken on the line 6—6 of Fig. 3.

Figs. 7, 8 and 9 are fragmental views illus-

trating the operation of the table tilting mechanism.

Fig. 10 is an enlarged sectional detail, with the section taken on line 10—10 of Fig. 1, showing the sliding link connection between one of the table sections and frame.

Fig. 11 is an enlarged sectional detail, with the section taken on the line 11—11 of Fig. 2, showing the latch device for holding the front legs of the device in their lowered supporting position.

Fig. 12 is an enlarged detail showing the upper end of the main operating lever of the tilting mechanism in section and the device supported therein for adjusting the tilting mechanism to either raise or lower the "head" end of the table.

Fig. 13 is a section taken on the line 13—13 of Fig. 4.

Similar reference characters indicate like parts in the several figures of the drawings.

As before stated, when the device is not in use as a tilting table, it is adapted to be closed up in such way as to take on the appearance of an ordinary couch. In order to provide for this, the device is made with an open rectangular frame 1 having corner supporting legs 2—2 and 3—3, those at the head of the frame being hinged thereto for a purpose to be hereinafter described.

Supported at the top of this frame is a table 4, which, when the device is closed up for use as a couch, rests directly upon the frame, as shown by dotted lines in Fig. 1, and serves as a couch top, the same preferably being an upholstered structure as shown in Figs. 1 and 6.

Attached to the under side of the frame 1 is a pair of rockers, 5 and 6, which are movable from a closed position at the under side of the device as shown in Fig. 2, assumed when the device is being used as a couch, to an open or downwardly pending position for resting on the floor, as shown in Fig. 1, assumed when the device is to be used as a tilting table. To provide for this adjustment of the rockers they are hinged to the opposite sides of the frame as shown at 7, 7, in Fig. 2.

When the device is to be used as a tilting table, the table proper 4, is adapted to be lifted from the frame as shown by full lines in Fig. 1, this being accomplished through connections comprising a pair of links 8, 8,

adjacent to the head end of the table, and a pair of bracket arms 9, 9, adjacent to the foot end of the table; the links 8 being pivoted at their opposite ends to the frame and 5 table at 10 and 11, respectively, and the depending bracket arms 9 being rigidly attached to the table and having pins 12 at their lower ends engaging in slotted guide plates 13, 13, attached to the opposite inner 10 sides of the frame 1. With these connections between the table and the frame, when the user lifts the table, the links 8 swing on their pivots 10, causing the table to move in a direction upwardly and longitudinally of 15 the frame to a position overhanging the head end of the latter as shown. At the same time the pins 12 on the bracket arms 9 move upwardly in the inclined slots of 20 the plates 13, 13—whereby to lift the lower or foot end of the table—until they reach the upper ends of the same and there limit the further raising of the table. These slots terminate at their upper ends in horizontally arranged portions 14 in order to provide a support for the table at its lower end. 25 When the table 4 is thus lifted, an open space is left between its lower end and the adjacent end of the frame which is adapted to be filled in by a supplemental foot section 30 15. This foot section 15, which is comparatively short, is adapted when not in use to rest upon a suitable support 16 (see Fig. 2) beneath the main table 4. As shown, this is connected with the frame by means of a pair 35 of links 17, 17, which at one end pivotally connect with the table section at 18, and at their opposite or lower ends have a sliding connection through headed pins 19 with horizontally arranged slotted channel irons 40 20, 20, attached to the opposite sides of the frame 1. In order to shift this foot section 15 to its open or raised position following the raising of the table 4 as described, its rear end is raised above the frame 1 and 45 then drawn backwardly until the links 17 reach the rear end of the slots in the channel irons 20, at which time a continued pull will cause the links to swing upwardly and raise the front end of the foot section to a position 50 flush with the adjacent end of the table 4, where it is held in position by two pairs of attached brackets 21 and 22, the brackets 21 engaging the adjacent end of the table 4 and the brackets 22 engaging a vertical wall 23 55 of the frame 1, as shown in Fig. 1.

In order that the rockers 5 and 6 may be lowered to their operative supporting position when the table 4 is raised and be swung up to their closed or inoperative position 60 when the table is lowered, I have provided a cable connection between the same, indicated at 25, which passes about two pulleys 26, 26, attached to the opposite sides of the table adjacent the rear end thereof, thence 65 over two pulleys 27, 27, carried by station-

ary bracket arms 28, 28, projecting inwardly from opposite sides of the frame 1, and from thence to the rockers, to which the opposite ends of the cable are connected at 29 and 30, as clearly shown in Figs. 1, 2 70 and 6. The length of this cable 25 is such that when the table is in its lowered or closed position, at which time the pulleys 26 thereon are positioned adjacent the rear end of the frame 1, the rockers will 75 be held in their raised or closed position, as shown by full lines in Fig. 2 and by dotted lines in Fig. 6, and when the table is raised, its consequent longitudinal movement shifts the pulleys 26 toward the pulleys 27 and thereby permits the lowering of the rockers to their supporting position. This operation will be clearly understood by reference to Fig. 1 of the drawings. In order that the rockers, when raised and lowered as described, may move in succession so as to avoid fouling one with the other, one of them is weighted whereby it will be first to lower and the last to raise. Any weighting means may be employed, but as here 80 shown I have attached to one of the rockers the table tilting mechanism to be hereinafter referred to.

As a means to lock the rockers in their lowered or operative position, I have provided a pair of latching devices, each of which comprises a latch 31 pivoted to a cross-bar 32 carried by the frame 1 and having a flange 33 adapted to engage a holding clip 34 attached to the rockers. In 95 order to have these latch devices automatically operated, each is connected through a pivoted link 35 with the bracket arms 9 on the table 4, whereby, when the table is raised, the latch devices will be swung downwardly 100 into latching position immediately following the lowering of the rockers, as shown by full lines in Fig. 1, and upon the lowering of the table will be drawn up and released from latching position, as shown by dotted lines 110 in Fig. 1.

When the device has been adjusted for use as a tilting table by the raising of the table and the lowering of the rockers, the supporting legs 2 at the head of the device 115 are adapted to be then raised from the floor so as to let the device rest on the rockers, whereby to permit of the device being tilted to a desired angle. These legs 2, which are suitable hinged to the frame 1 as before described, may be swung to an inoperative position by any suitable means. In the present case, they are carried by a cross-head 36 to which is connected a spring 37 that is normally operative to swing the legs to their 120 raised position, the said legs being held to their lowered position and against the pull of said spring by a latch device 38 (see Figs. 2 and 11) which is pivoted to the cross-head at 38' and adapted to engage a latch pin 39 130

attached to the frame 1. With this construction, when it is desired to swing the legs to their inoperative position, the user simply releases the latch lever 38 from the latch pin 5 39, whereupon the legs will be automatically swung upward under the action of the spring 37, as shown in Fig. 1.

I will next describe the means for tilting the table to a desired angle of inclination 10 and holding it in its adjusted position. It will be understood of course, in view of the intended home use of the device, that it is desirable that the device should be capable of being readily tilted to any desired angle 15 by the user when in a reclining position on the table. Means to this end have therefore been provided. These means comprise a guide member 40 rigidly attached to the rocker frame 5 and having an arcuate slot 20 41 following generally the curvature of the supporting rocker, a runner 42 having at one end a roller 43 for resting upon the floor and adjacent its opposite end having a plurality of rollers 44 engaging the member 25 40 within the slot 41 therein, and means including a pair of ratchet pawls 45 and 46 engaging ratchet teeth 47 on the upper curved edge of the runner 42 for effecting a longitudinal movement of the runner relative 30 to the guide member 40 as permitted by the travel of the rollers 44 in the slot 41. The supporting rockers 5 and 6 are so positioned relative to the table 4 that the weight of the latter will bear upon the runner 35 42 when the front legs 2 are swung up to their inoperative position, as shown in Fig. 1. Thus it will be understood that if the runner is permitted to shift forwardly, that is, toward the left as viewed in Fig. 1, the head end of the table will be permitted 40 to lower through the coaction of the guide slot 41 with the rollers 44, and if the runner is shifted in the opposite direction the said head end of the table will be caused to rise. 45 Such movement of the runner relative to the guide member 40 is controlled by the ratchet pawls 45 and 46 by means to be presently described.

In order to provide a firm connection between the guide member 40 and associated runner 42, said guide member is formed of two plates 40', 40'', secured together in spaced relation, between which the runner extends and operates, as most clearly shown 50 in Figs. 4, 5 and 6, wherein the runner at its rear end is also shown as being formed of two plates secured together in spaced relation and with the roller 43 mounted between them.

60 The ratchet pawl 45 hereinbefore referred to is pivoted to the member 40 at 50, and is yieldingly held by a connecting spring 51 in a normal position with its free end in engagement with one of the teeth 47 on the runner 42, whereby the table is held against

downward tilting movement. This pawl 45 therefore acts as a retaining pawl. The other pawl 46 acts as an operating pawl and is pivoted to an arm 52 rigidly attached to a rock shaft 53 which is provided with an operating lever 54, the said shaft being mounted in the member 40 at one side of the rocker 5 and in a bracket arm 55 depending from the frame 1 at the opposite side of said rocker, as clearly shown in Figs. 4 and 6. When the head end of the table is to be tilted downward, it is necessary to release the retaining pawl from its engagement with the teeth of the runner in order to permit of such movement, and a consequent outward movement of the runner is caused by the walls of the arcuate slot 41 in the guide member 40 acting against the rollers 44 on the runner, as will be understood by reference to Fig. 8. 80 This releasing of the retaining pawl is accomplished at follows: Preliminary to the releasing operation, a tongue 60 is projected, by means to be hereinafter described, into a position between the top of the pawl 46 and a spring 61 attached to the under side of the pawl 45, as shown in Figs. 3 and 7, as a means to place said spring under tension. At this time the pawls will be in the position shown in Fig. 7, with the retaining pawl 45 in holding engagement with a tooth on the runner. Thereafter, when the user wishes to tilt the head of the table downwardly, he will pull the operating lever 54 slightly backward, or in a direction toward the head of the table, and thereby cause the operating pawl 46 to force the runner forward just sufficiently to release the retaining pawl from engagement with its co-operating tooth and permit the same being raised under the action of the spring 61 to a position above said tooth, as indicated by dotted lines in Fig. 9, the tension of the spring 61 being sufficient to overcome that of the upper spring 51 in effecting this release of the pawl. After the pawl 45 is thus released, the table will lower under the weight of the user and force the runner outward, as indicated by dotted lines in Fig. 8, until the retaining pawl engages the succeeding tooth of the runner, the lowering of the pawl into position for engagement with such succeeding tooth being permitted by reason of the dropping of the tongue 60 from its position of tensioning engagement with the spring 61, which is permitted by the withdrawal of the operating pawl 46 from thereunder, as shown in Fig. 8. The tongue 60, however, is held in its raised spring-tensioning position by the pawl 45 sufficiently long after the initial releasing of the retaining pawl from the engaging ratchet tooth—shown by dotted lines in Fig. 9—to permit of the top of the tooth passing beneath the toe of said pawl. Unless the 100

toe of the retaining pawl was so supported until the top of the tooth had passed thereunder, it would of course drop back into its original position of engagement with the 5 tooth and so prevent outward movement of the runner.

The tongue 60 as here shown is a lateral extension of a member 63 pivoted at 64 to a plate 65 which is pivotally mounted on the 10 inner side of the guide member 40, by a pivot pin 66, the said tongue being adapted to extend through an opening in the member 40 to its position for coöperation with the spring 61 and being limited in its down- 15 ward movement so as not to engage with the runner teeth 47 by a stop pin 67 on the plate 65 engaging the lower edge of the pivoted member 63.

During the lowering of the table as per- 20 mitted by the shifting of the retaining pawl from one ratchet tooth to the succeeding one as just described, the operating pawl 46 is carried backward by the engaging ratchet tooth of the shifting runner until the parts 25 are locked by the engagement of the retaining pawl with the succeeding ratchet tooth. When the operating pawl is thus moved backward, a rearwardly projecting heel portion 68 thereon is brought into engagement 30 with a downwardly-pressing spring arm 69. Thereafter, if a further lowering of the head end of the table is desired, the user will push forward on the lever 54 to move the pawl 46 backward slightly from its en- 35 gaging ratchet tooth, whereupon the pawl will be rocked on its pivot under the action of the spring 69 to raise the toe end thereof upwardly from its tooth engaging position, as indicated by dotted lines in Fig. 8. This 40 will permit the pawl 46 to be again advanced by the operating lever to a position beneath the tongue 60, as shown in Figs. 7 and 9, and there raise said tongue to tension the spring 61 and permit of another releasing 45 of the retaining pawl, in the manner just described. This releasing operation may of course be repeated until the table has been tilted downwardly to the desired angle.

The arm 69 for engaging with the heel 50 of the pawl 46 as just described, is connected with the member 40, at 70, and is yielding in order that it may be free to move upwardly when engaged by the heel of said pawl, under the conditions to be hereinafter 55 described, without producing any movement of the pawl. When it is desired to have said arm 69 act to rock the pawl to releasing position as just described, however, a tongue 71 on the pivoted member 65 is adapted to 60 be projected laterally into a position of engagement with the upper edge of the arm 69, as shown in Figs. 7, 8 and 9, and hold the same stationary whereby it will function in coöperation with the heel of the pawl in 65 the manner described.

In order to elevate the head end of the table from its lowered position, the pivoted member 65 is first operated to withdraw the tongues 60 and 71 from their positions for coöperation with the pawls 45 and 46 as 70 shown in Fig. 4. This leaves the pawls free to operate in usual manner for advancing one part relative to another and retaining it in its advanced position. For instance, when the user desires to raise the table he 75 will operate the lever 54 in a manner to advance the runner, through the engagement of the pawl 46 with the successive ratchet teeth 47, the advance of the runner relative to the guide member 40 being maintained 80 by the retaining pawl 45 dropping into engagement with the successive ratchet teeth in usual manner. In this way the table may be tilted from the lowered position shown in Fig. 8 to the raised position shown in 85 Figs. 1 and 3.

It will be understood from the foregoing that when the table is to be tilted downwardly, the tongues 60 and 71 should be projected forwardly into operative position 90 for coöperation with the pawls 45 and 46, and that when the table is to be tilted upwardly, the said tongues should be withdrawn from their said position for coöperation with the pawls. In order that this may 95 be conveniently done by the user without change of his reclining position on the table, I have provided a means that may be operated from the handle end of the operating lever for rocking the pivoted member 65 so 100 as to shift the supported tongues to and from their operative position. These means comprise a pin 75 slidably mounted in a bore of the rock shaft 53 with one end projecting beyond the latter at its inner end for 105 engagement with the upper end of the pivoted tongue-carrying member 65, and its opposite end extending into engagement with an inclined or wedge surface 76 at the lower end of a rod 77, which is supported 110 for vertical movement within the operating lever 54, the latter being made tubular for this purpose. Said rod 77 at its upper end is pivotally connected to a small lever 78, which is pivoted to the handle end of the 115 lever 54, at 79, and is formed with its operating end extending upwardly through an opening in said handle end for operating between two stops 81 and 82 thereon, as 120 shown in Fig. 12. When the lever 78 is in the full line position shown in Fig. 12, the rod 77 will be raised with its lower end above the pin 75, as shown in Fig. 6, whereby the pivoted member 65 may be shifted by a spring, such as 83, to its position with the tongues 60 and 71 withdrawn to their inoperative positions, as shown in Fig. 4. By swinging said lever 78 over into engagement with the opposite stop 82, as shown by 125 dotted lines in Fig. 12, the rod 71 will there- 130

by be lowered and the wedge at its lower end forced downward into engagement with the pin 75 to move the latter inwardly and thereby rock the pivoted member 65 in a 5 direction to project the tongues 60 and 71 to their operative positions, as and for the purpose described. It will thus be seen that the user has only to shift the small lever 78 at the handle end of the operating lever 54 10 to adapt the tilting mechanism for either raising or lowering the head end of the table 4.

When the user of the device lies on the table 4 on his back, the operating lever 54 15 should be in the upright or vertical position shown in Figs. 1 and 6 for convenient manipulation by the user. In some uses of the device, however, it is necessary for the user to lie on the table face downward. In 20 such cases, the operating lever, for convenient manipulation, should be in a substantially horizontal position. To provide for such change in positions of the lever, the latter is loosely mounted on the end of the 25 rock shaft 53 and has an adjustable connection with a notched collar keyed fast to said rock shaft, as shown in Fig. 13. This connection is effected by means of a spring 30 latch 89, mounted in a housing 90, fixed to the lever 54 at its lower end (see Figs. 4 and 6), which latch engages either one of a plurality of notches 91, in the collar 88, according to the position desired for the lever. 35 The collar 88 is shown as being formed with a hub 92, to which is rigidly attached an arm 93, having two stop surfaces 94, 94, for engaging with a stationary pin 95, on the frame, to limit the operating throw of 40 the lever 54 and also hold the latter within limits to its adjusted positions.

What I claim is:—

1. In a device of the character described, a frame, a table movable thereon, means 45 comprising a rocker for supporting the table in a tiltable position, said rocker being laterally adjustable to and from an operative supporting position, latching means independent of the rocker for locking said rocker 50 to its operative position, and means operated upon the movement of the table relative to the frame to shift said latching means to and from its locking position. 55 2. In a device of the character described, a frame, a table vertically movable relative thereto, means comprising a rocker for supporting the table in a tiltable position, said rocker being adjustable to and from an operative supporting position, latching means 60 for locking the rocker to its operative position, and connections between the table and latching means automatically operative upon the raising and lowering of the table to shift the latching means to and from its 65 locking position.

3. In a device of the character described, a frame, a table movable thereon, means comprising a rocker for supporting the table in a tiltable position, said rocker being pivoted to the frame for movement to and from 70 its operative supporting position, and a connection between the table and rocker automatically operative upon the shifting of the table relative to the frame to cause a shifting of the rocker to and from its operative 75 supporting position.

4. In a device of the character described, a frame, a table supported by said frame and being vertically movable relative thereto, means comprising a pair of rockers for 80 supporting the table in a tiltable position, said rockers being pivoted to the frame for movement to and from their operative supporting positions, and a connection between the table and rockers automatically operative 85 upon the raising and lowering of the table to cause a shifting of the rockers to and from their operative supporting positions.

5. In a device of the character described, a frame, a table supported by said frame 90 and being movable longitudinally thereof, means comprising a pair of rockers for supporting the table in a tiltable position, said rockers being pivoted to the frame for movement from a lowered supporting position to 95 a raised closed position beneath the frame, and a flexible connection between the table and the rockers operative to raise the rockers to their closed position upon the movement of the table in one direction and to permit the lowering of the rockers to operative 100 supporting position upon the movement of the table in the opposite direction.

6. In a device of the character described, a frame, a table supported by said frame 105 and being movable longitudinally thereof, means comprising a pair of rockers for supporting the table in a tiltable position, said rockers being pivoted to the frame for swinging movement in a direction transversely of the frame to and from their operative supporting positions and one of the rockers being heavier than the other, and a cable connected at its opposite ends with the rockers and at an intermediate point 110 having a sliding connection with the table, whereby, upon the movement of the table longitudinally in one direction the rockers will be successively raised to their inoperative positions and upon the movement of the 115 table in the opposite direction the rockers will be successively lowered to their operative positions.

7. In a device of the character described, a frame, a table supported by said frame 120 and being movable longitudinally thereof, means comprising a pair of rockers for supporting the table in a tiltable position, said rockers being pivoted to the frame for swinging movement in a direction trans- 125

130

versely of the frame to and from their operative supporting positions and one of the rockers being heavier than the other, a pulley carried by the table, and a cable connected at its opposite ends with the rockers and at an intermediate point passing over said pulley on the table, whereby, upon the movement of the table longitudinally in one direction the rockers will be successively raised to their inoperative positions and upon the movement of the table in the opposite direction the rockers will be successively lowered to their operative positions.

8. In a device of the character described, a frame, a table supported by said frame and being movable relative thereto, means comprising a pair of rockers for supporting the table in a tilttable position, said rockers being connected to the frame for movement from a lowered supporting position to a raised closed position beneath the frame, a flexible connection between the table and the rockers operative to raise the rockers to their closed positions upon the movement of the table in one direction and to permit the lowering of the rockers to their operative supporting positions upon the movement of the table in the opposite direction, latching means for locking the rockers in their lowered operative positions, and connections between the table and latching means operated by the movement of the table in one direction to cause the latching means to lock the rockers when in their lowered positions.

9. In a device of the character described, a frame, a table supported by said frame and being movable relative thereto, means comprising a pair of rockers for supporting the table in a tilttable position, said rockers being connected to the frame for movement from a lowered supporting position to a raised closed position beneath the frame, a flexible connection between the table and the rockers operative to raise the rockers to their closed positions upon the movement of the table in one direction and to permit the lowering of the rockers to their operative supporting positions upon the movement of the table in the opposite direction, latching means for locking the rockers in their lowered operative positions, and connections between the table and latching means operated by the movement of the table in one direction to cause the latching means to automatically release the rockers preliminary to their being raised to inoperative position.

10. In a device of the character described, a frame, a table supported by said frame and being movable relative thereto, means comprising a pair of rockers for supporting the table in a tilttable position, said rockers being connected to the frame for movement from a lowered supporting position to a

raised closed position beneath the frame, latching means for locking the rockers to their lowered supporting position, and connections between the table and the rockers and latching means, whereby, upon the movement of the table in one direction, the rockers will be lowered to supporting position and then latched in such position, and upon the movement of the table in the opposite direction the latching means will release the rockers and the latter be then raised to their inoperative position.

11. In a device of the character described, a frame having means for supporting it in both stationary and tilttable positions, a table adapted to rest thereon, and connections between the table and frame for causing the table to assume an inclined position relative to the frame when raised from the latter, and means for holding the table in such position relative to the frame comprising a supplemental table section.

12. In a device of the character described, a frame having means for supporting it in both stationary and tilttable positions, a table adapted to rest thereon, connections between the table and frame for causing the table, when raised from the frame, to move longitudinally of the latter and assume an inclined position relative thereto, and a supplemental table section having means for engaging the frame and the main table for holding the latter in its raised position relative to the frame.

13. In a device of the character described, a frame having means for supporting it in both stationary and tilttable positions, a table adapted to rest thereon, connections between the table and frame for causing the table, when raised from the frame, to move longitudinally of the latter, means for limiting the movement of the table relative to the frame in one direction, and a supplemental table section having a pivoted link connection with the frame and being movable to a position for engaging the main table and limiting its movement relative to the frame in the opposite direction.

14. In a device of the character described, a frame having means for supporting it in both stationary and tilttable positions, a table adapted to rest thereon, pivotal link connections between the table and frame for causing the table, when raised from the frame, to move longitudinally of the latter, means for limiting the movement of the table relative to the frame in one direction, and a supplemental table section having a pivoted link connection with the frame and being movable to a position for engaging the main table and limiting its movement relative to the frame in the opposite direction.

15. In a device of the character described, a table, and supporting means therefor com-

- prising two floor-engaging members one of which is slidably adjustable on the floor relative to the other in a direction to permit tilting of the table, operating means for controlling the shifting of the adjustable member relative to the other, and locking means for holding said adjustable member stationary relative to the other member at different points in its range of adjustment.
- 5 16. In a device of the character described, a table, supporting means therefor comprising two floor members one of which is slidably adjustable on the floor relative to the other in a direction to permit downward tilting of the adjacent end of the table under the action of gravity, operating means for controlling the shifting of said adjustable member, and locking means for holding said adjustable member stationary relative to the other member at different points in its range of adjustment.
- 10 17. In a device of the character described, a table, supporting means therefor comprising two floor members one of which is slidably adjustable on the floor relative to the other in a direction to permit downward tilting of the adjacent end of the table under the action of gravity, operating means for shifting said adjustable member in a direction to raise the adjacent end of the table, and locking means for holding said adjustable member stationary relative to the other member at different points in its range of adjustment.
- 15 18. In a device of the character described, a table, supporting means therefor comprising two floor members one of which is slidably adjustable on the floor relative to the other in a direction to permit downward tilting of the adjacent end of the table under the action of gravity, operating means for holding said adjustable member stationary relative to the other member at different points in its range of adjustment.
- 20 19. In a device of the character described, a table, supporting means therefor comprising two floor members one of which is slidably adjustable on the floor relative to the other in a direction to permit downward tilting of the adjacent end of the table under the action of gravity, and a guide member carried by the table co-acting with said adjustable floor member for controlling the tilting movement of the table.
- 25 20. In a device of the character described, a table, supporting means therefor comprising two floor members one of which is slidably adjustable on the floor relative to the other in a direction to permit downward tilting of the adjacent end of the table under the action of gravity, operating means for shifting said adjustable member in a direction to raise the adjacent end of the table, and locking means for holding said adjustable member stationary relative to the other member at different points in its range of adjustment.
- 30 21. In a device of the character described, a table, supporting means therefor comprising two floor members one of which is slidably adjustable on the floor relative to the other in a direction to permit downward tilting of the adjacent end of the table under the action of gravity, and a guide member carried by the table having an arcuate guide co-acting with said adjustable floor member for controlling the tilting movement of the table.
- 35 22. In a device of the character described, a table, supporting means therefor comprising two floor members one of which is slidably adjustable on the floor relative to the other in a direction to permit downward tilting of the adjacent end of the table under the action of gravity, and a guide member carried by the table having an arcuate guide co-acting with said adjustable floor member for controlling the tilting movement of the table.
- 40 23. In a device of the character described, a table, supporting means therefor comprising a rocker and a guide both connected with the table, and a floor runner bodily adjustable longitudinally of the rocker and co-acting with the guide for controlling the tilting of the table.
- 45 24. In a device of the character described, a table, supporting means therefor comprising a rocker and a guide both connected with the table, a floor runner adjustable relative to the rocker and co-acting with the guide for controlling the tilting of the table, and means co-operating directly with the runner for adjusting it relative to the guide.
- 50 25. In a device of the character described, a table, supporting means therefor comprising a rocker and a guide both connected to the table, a floor runner adjustable relative to the rocker and co-acting with the guide for controlling the tilting of the table, said runner being provided with a rack, and means comprising a lever and pawl for co-operating with said rack to adjust the runner relative to the guide and rocker.
- 55 26. In a device of the character described, a table, supporting means therefor comprising a rocker and a guide both connected to the table, a floor runner adjustable relative to the rocker and co-acting with the guide for controlling the tilting of the table, said runner being provided with a rack, means comprising a lever and pawl for co-operating with said rack to adjust the runner relative to the guide and rocker, and a locking pawl co-operating with the rack to hold the runner in adjusted position.
- 60 27. In a device of the character described, a table, supporting means therefor comprising a rocker and an arcuate guide both con-

5 nected with the table, a floor runner adjustable relative to the rocker and co-acting with the guide for controlling the tilting of the table, and means coöperating directly with the runner for adjusting it relative to the guide.

10 28. In a device of the character described, a table, supporting means therefor comprising a rocker and a guide both connected with the table, said guide being formed with two spaced members, a floor runner slidably fitted to the space between the guide members and co-acting with the guide for controlling the tilting of the table, and means operating directly with the runner for adjusting it relative to the guide.

15 29. In a device of the character described, a table, supporting means therefor comprising a rocker and a guide both connected with the table, said guide being formed with two spaced members each of which is provided with an arcuate guide slot, a floor runner slidably fitted to the space between said members and provided with rollers engaging the members within the said slots therein for controlling the tilting of the table, and means coöperating directly with the runner for adjusting it relative to the guide.

20 30. In a device of the character described, a table, supporting means therefor comprising two members one of which is adjustable relative to the other for effecting tilting of the table, means for locking said adjustable member against movement relative to the other member at different points in its range of adjustment to thereby hold the table stationary, and means for releasing the locking means to permit relative movement of said members in a direction permitting of the 25 downward tilting of the table under the action of gravity.

30 31. In a device of the character described, a table, supporting means therefor comprising two members one of which is adjustable relative to the other for effecting tilting of the table, automatic means for locking said members against relative movement to thereby hold the table stationary, and means for releasing the locking means to permit relative movement of said members in a direction permitting of the downward tilting of the table under the action of gravity.

35 32. In a device of the character described, a table, supporting means therefor comprising two members one of which is adjustable relative to the other, means for moving said adjustable member in a direction for effecting an upward tilting of the table, means for locking said adjustable member against movement relative to the other member at different points in its range of adjustment to thereby maintain the table stationary in its adjusted position, and means for releasing said locking means to permit of a reverse

40 movement of the adjustable member and a consequent downward tilting of the table under the action of gravity.

45 33. In a device of the character described, a table, supporting means therefor comprising two members one of which is adjustable relative to the other and adapted to rest on the floor, means for moving said floor member in one direction to effect an upward tilting of the table, means for locking said floor member in adjusted position, means for releasing said locking means to permit of a reverse movement of the floor member and a consequent downward tilting of the table under the action of gravity, and means for rendering said releasing means either operative or inoperative.

50 34. In a device of the character described, a table, supporting means therefor comprising two members one of which is adjustable relative to the other and adapted to rest on the floor, means for moving said floor member in one direction to effect an upward tilting of the table, means for locking said floor member in adjusted position, and means for releasing said locking means to permit of a reverse movement of the floor member and a consequent downward tilting of the table under the action of gravity, said releasing means including a shiftable element effective to render the same either operative or inoperative.

55 35. In a device of the character described, a table, supporting means therefor comprising two members one of which is adjustable relative to the other and adapted to rest on the floor, said floor member being provided with a rack, actuating means for moving said floor member in one direction to effect an upward tilting of the table, a pawl engaging the said rack on the floor member to hold the latter against reverse movement, and controlling means coöoperative with the actuating means for effecting a release of the pawl from locking engagement with the rack whereby to permit a reverse movement of the floor member, said controlling means being adjustable to and from an operative position for coöperation with the actuating means.

60 36. In a device of the character described, a table, supporting means therefor comprising two members one of which is adjustable relative to the other and adapted to rest on the floor, said floor member being provided with a rack, actuating means including a lever for moving said floor member in one direction to effect an upward tilting of the table, a pawl engaging the said rack on the floor member to hold the latter against reverse movement, controlling means coöoperative with the actuating means for effecting a release of the pawl from locking engagement with the rack whereby to permit a reverse

- movement of the floor member, said controlling means being adjustable to and from an operative position for coöperation with the actuating means.
- 5 37. In a device of the character described, a table, supporting means therefor comprising a rocker and a guide both connected to the table, a floor runner adjustable relative to the rocker and co-acting with the guide
- 10 for controlling the tilting of the table, said runner being provided with a rack, means comprising a lever and pawl for coöperating with said rack to advance the runner in a direction to raise the table, a locking pawl
- 15 for engaging the rack to hold the runner against reverse movement, and controlling means coöperating directly with said pawls to effect a release of the same from the rack whereby to permit a reverse movement of
- 20 the runner.
38. In a device of the character described, a table, supporting means therefor comprising a rocker and a guide both connected to the table, a floor runner adjustable relative to the rocker and co-acting with the guide
- 25 for controlling the tilting of the table, said runner being provided with a rack, means comprising a lever and pawl for coöperating with said rack to advance the runner in a direction to raise the table, a locking pawl
- 30 for engaging the rack to hold the latter against reverse movement, and controlling means coöperating directly with said pawls to effect an alternate release of the same
- 35 from the rack whereby to permit and control a reverse movement of the runner.
39. In a device of the character described, a table, supporting means therefor comprising a rocker and a guide both connected to
- 40 the table, a floor runner adjustable relative to the rocker and co-acting with the guide
- 45 for controlling the tilting of the table, said runner being provided with a rack, means comprising a lever and pawl for coöperating with said rack to advance the runner in a direction to raise the table, a locking pawl
- 50 for engaging the rack to hold the runner against reverse movement, controlling means coöperating directly with said pawls to effect a release of the same from the rack whereby to permit a reverse movement of the runner, an adjustable member carrying
- said controlling means, and means for shifting said member to move the controlling means to and from an operative position. 55
40. In a device of the character described, a table, supporting means therefor comprising a rocker and a guide both connected to the table, a floor runner adjustable relative to the rocker and co-acting with the guide
- 60 for controlling the tilting of the table, said runner being provided with a rack, means comprising a lever and pawl for coöperating with said rack to advance the runner in a direction to raise the table, a locking pawl
- 65 for engaging the rack to hold the runner against reverse movement, and controlling means comprising two spring members for coöperating directly with said pawls to effect a release of the same from the rack
- 70 whereby to permit a reverse movement of the runner.
41. In a device of the character described, a table, and supporting means therefor comprising two floor-engaging members one of
- 75 which is adjustable relative to the other in a direction to permit tilting of the table, means for controlling the shifting of the adjustable member relative to the other, a hand operating lever for actuating said controlling means, and an adjustable connection between the lever and controlling means
- 80 for rigidly holding the lever at different desired angles with respect to the controlling means, for the purpose set forth. 85
42. In a device of the character described, a table, and supporting means therefor comprising two floor-engaging members one of
- 85 which is adjustable relative to the other in a direction to permit tilting of the table, and means for controlling the shifting of the adjustable member relative to the other, said controlling means comprising a rock-
- 90 shaft, an operating lever adjustably connected therewith, and means for rigidly holding the lever on said shaft at different desired angles, for the purpose set forth.
- Signed at New York, in the county of New York, and State of New York, this 27th day of November, A. D. 1917.
